(57) **CLAIM**

The ornamental design for a sauna heater, as shown and described.

DESCRIPTION

FIG. 1 is a perspective view of the sauna heater;
FIG. 2 is a perspective front view of the sauna heater;
FIG. 3 is a perspective right side view of the sauna heater;
FIG. 4 is a perspective left side view of the sauna heater;
FIG. 5 is a perspective rear view of the sauna heater;
FIG. 6 is a perspective top view of the sauna heater; and,
FIG. 7 is a bottom view of the sauna heater.

Broken lines shown in the drawings are for purposes of illustrating portions of the sauna heater and form no part of the claimed design.
